Inventor

By his Attorneys Dodson & Roe.

UNITED STATES PATENT OFFICE.

JOHN LACKNER, OF LONG ISLAND CITY, NEW YORK.

DESIGN FOR A NOVELTY CAP.

60,795.

Specification for Design. Patented Apr. 11, 1922.

Application filed December 2, 1921. Serial No. 519,522. Term of patent 7 years.

To all whom it may concern:

Be it known that I, JOHN LACKNER, a citizen of the United States, residing at Long Island City, in the county of Queens and State of New York, have invented a new, original, and ornamental Design for a Novelty Cap, of which the following is a specification, reference being had to the accompanying drawing, forming part thereof.

The figure is a perspective view of a novelty cap, showing my new design.

I claim:

The ornamental design for a novelty cap, as shown.

JOHN LACKNER.
